YARN FEEDING MECHANISM FOR KNITTING MACHINES

Robert H. Lawson, Pawtucket, and Arthur N. Cloutier, Lonsdale, R. I., assignors to Hemphill Company, Central Falls, R. I., a corporation of Massachusetts

Application July 31, 1934, Serial No. 737,808

12 Claims. (Cl. 66—139)

The present invention is primarily concerned with the knitting of plated fabric and more particularly with a means for readily interchanging the plating and/or other yarns.

In the drawings:

Fig. 1 is a view of a knitting machine having the present improvements applied thereto;

Fig. 2 is a plan view of the machine shown in Fig. 1, certain parts being omitted;

Fig. 3 is a fragmentary view, partly in section, of a portion of the latch ring shown in Fig. 2;

Fig. 4 is a fragmentary elevational view partly in section taken along the line 4—4, Fig. 3;

Fig. 5 is an enlarged elevational view showing the latch ring and levers for controlling the interchanging of the plating threads;

Fig. 6 is a fragmentary view in elevation taken at right angles to the view shown in Fig. 5;

Fig. 7 is a view in elevation taken at right angles to the view shown in Fig. 1 showing cam drums for controlling the plating threads;

Fig. 8 is a plan view showing the levers and one of the drums of Fig. 7;

Fig. 9 is a detail view taken along the line 9—9, Fig. 8; and

Fig. 10 is a sectional view in elevation of the latch ring showing the feeding of main and plating threads to the needles.

The machine shown is an improvement upon that shown in the patent to Hemphill 933,443, September 7, 1909, and in the patents to Lawson 1,605,896, November 2, 1926 and Re. 16,584, April 5, 1927, although the mechanism is obviously adaptable to other types of knitting machines.

The needle cylinder 1 is mounted in a circular base 2 being driven to rotate or reciprocate in the usual manner as by means of pulleys 3. The various knitting operations at times are controlled through the agency of a pattern chain 4 and cams on the several drums 5, 6 and 7, all of which are fast to the main cam shaft 8, the chain 4 being periodically and constantly racked independently of the shaft 8. The usual thread or yarn lever box 9 is provided, being secured to

an extension of the circular base 2 and upstanding therefrom. The needles 10 are slidably mounted in tricks or grooves in the needle cylinder 1 being controlled in their movements by cams mounted on or adjacent to the cam ring 11 and in some cases being selected by jacks (not shown). At the upper end of the needle cylinder is attached, to rotate with the needle cylinder, a sinker head 12 the movements of the sinkers (not shown) being controlled in the usual manner by cams in a sinker cam cap 13. A

so-called latch ring 14 is pivotally connected to the machine frame in the usual manner, the radial extension 15, Fig. 10, providing means for pivotally mounting the latch ring on the frame. A cam block 16 is provided for imparting movements to the needles to effect the knitting of fabric by causing the needles to knit one or more of the yarns and simultaneously therewith a plating thread. Mounted on the said cam block are the usual narrowing picks such as 17. 5 Mounted upon the yarn lever box 9 and fastened thereto as by screws 18 is a plate 19, connections (not shown) passing up through the yarn lever box 9 and actuating the yarn levers 20 in any desired order, as usual in machines of the 15 type shown in the drawings.

Forming part of the plate 19 and extending laterally therefrom (Fig. 2) is an arm 21 provided with a strengthening rib 21'. To the outer or free end of arm 21 is connected in any suitable manner 20 an upstanding block 22 slotted for the reception of a series of levers, three being shown in the present instance and designated by the numerals 23, 24 and 25. Removably connected to open ended slots in said levers 23, 24 and 25 are links 26, 27 and 28 said links depending from the outer end of said levers and being removably connected at their lower ends (Fig. 7) in open ended slots provided in one end of each of levers 29, 30 and 31. The levers 29, 30, 31 are pivotally connected intermediate their ends as at 32 to the machine frame. The other arms of the levers 29, 30, 31 have adjustably fastened thereto toes or followers 33, 34, 35 respectively which rest upon the surface of a drum 36 or upon suitably positioned cams, such as 37, carried thereby. The cam drum 36 is fixedly mounted upon a shaft 38 to which circumferential movements are automatically and intermittently imparted in any suitable manner. The shaft may be supported 35 in suitable bearings carried by upright brackets such as 39 attached to the machine frame as by 40 screws or bolts 40.

A plate 41, Figs. 7, 8 and 9, serves two purposes, namely, to maintain the levers 29, 30 and 45 31 in proper alignment with their respective cams on the cam drum 36 and to elevate all of the toes of the levers 29, 30 and 31 thereby elevating the auxiliary yarn levers presently to be described. The plate 41 is provided with two 50 upstanding arms 42, 43 between which arms the levers 29, 30, 31 move. The lever 29 has fastened thereto by means of screws 44 a plate or bracket 45 between ears of which is received the arm 42 of the plate 41, the plate 41 being 55

thereby maintained in proper relation with respect to the levers 29, 30 and 31. The plate 41 is adjustably connected as by means of screws 46 to a depending link 47 to the lower end of which 5 is pivotally and adjustably connected a lever 48. The lever 48 is pivoted intermediate its end as at 49 to the machine frame and at its other end is provided with a toe or follower 50 which is maintained in contact with the surface of the 10 drum 5 or cams 51 and 52 which are fastened to the surface of the drum. The toe 50 is maintained in contact with the drum or cams 51 and 52 thereon by the weight of the plate 41, link 47, etc. and further by springs that will be 15 presently described.

In Fig. 10 a main or body thread or yarn 53 is shown as being fed to the needles with a plating thread or yarn 54. The yarns such as 53 are interchangeably fed to the needles in the usual 20 manner through the usual thread guides 20, while plating threads such as 54 are interchangeably fed to the needles through guides such as 55, 56, 57, Figs. 3, 4 and 10. In order to secure better plating effects it is desirable that the plating 25 and body threads be fed to the needles at separated points and maintained in separated relation; to effect this desirable object the auxiliary or plating thread levers 55, 56, 57 are slidably and vertically mounted in a block 58 which is 30 recessed or grooved for that purpose at 59, Fig. 3. A plate 60 which is fastened to the block 58 as by screws 61 serves to maintain the guides 55, 56, 57 within the slot or recess 59. The block 58 upstands from and is integral with or fastened 35 to a bracket plate 62 which in turn is adjustably fastened to the latch ring 14 as by means of screws 63 and elongated slots 64 provided in the plate 62. Adjustment of the plate 62 and consequently of the yarn levers 55, 56, 57 permits 40 the said yarn levers to be properly adjusted with respect to the main feeding point and with respect to the needles and a cutout or recessed portion 65 provided in the latch ring 14.

The recessing of the latch ring at 65 permits 45 the ends of the guides 55, 56, 57 to pass down between the needles and the latch ring 14 as indicated in Fig. 4.

The yarn levers 55, 56, 57 at their upper ends extend laterally as at 66, 67, 68. From the free 50 ends of the arms or extensions 66, 67 and 68 pins 69, 70 and 71 extend laterally and to these pins are pivotally connected levers 72, 73 and 74 respectively, said levers 72, 73, 74 being maintained in engagement with their respective pins as by 55 means of screws 75 which are in threaded engagement with their respective pins, 69, 70, 71. As will be noted from inspection of Figs. 2 and 5 the extension 66, 67, 68 and their respective pins 69, 70, 71 are of different lengths, the shortest 60 extension 66 being provided with the longest pin 69 and the longest extension 68 being provided with the shortest pin 71, such construction providing a compact yarn change mechanism. Connected to the latch ring 14, Figs. 5 and 6, is an upstanding bracket 76, screws such as 77 serving 65 to clamp the bracket 76 to the latch ring 14. The bracket 76 at its upper portion extends at right angles the resultant horizontal portion 78 providing a suitable support for the levers 72, 73, 74. 70 Also the horizontal portion 78 of the bracket 76 is provided with a series of holes through which pass pins 79, 80 and 81 which are headed at their upper portions to seat upon the plate 78. The pins 79, 80 and 81 extend downwardly through 75 the holes in the plate 78 being engaged by levers

23, 24, 25 respectively. As hereinbefore described, the levers 23, 24, 25 are automatically controlled in their pivotal movements by links 26, 27, 28 and through them by the cams on the drum 36. When a cam such as 37 engages a toe 5 of a lever such as 33, the corresponding lever is rocked and its connecting lever 23 is also rocked thereby elevating the pin 19 which engages a lever 57 from the position shown in Fig. 4 to an inoperative non-feeding position. Conversely 10 when a lever 29, 30 or 31 drops to a position in contact with the surface of the drum 36 the corresponding lever such as 57 drops to the position shown in Fig. 4, the movement being accelerated by one of a series of leaf springs 82, one such 15 spring being provided for each lever 12, 13, 14. As shown in Fig. 5 the free ends of the leaf springs are shaped as at 83 to straddle their respective levers 12, 13, 14 thereby maintaining the said levers in proper lateral position so as not 20 to move out of contact with their respective pins 19, 20, 21.

When it becomes necessary to rethread the levers 55, 56, 57 a lever 84 is rocked, one arm of such lever taking under the levers 12, 13, 14 thus 25 rocking them on their pivot 85 and consequently elevating the yarn levers 55, 56, 57 to such a position as to be conveniently threaded. The lever 84 is also mounted for pivotal movements on the pin 85 which pin passes through holes 30 provided in an upstanding portion of the bracket 78 being retained in axial position by means of a screw 86. A cap plate 87 surmounts the upper portion of the bracket 78 being retained in position as by means of screws such as 88 some of 35 which may also serve to retain the leaf springs in fixed position with respect to their levers 12, 13, 14.

At 89 is shown a yarn controlling mechanism similar to that shown in Lawson et al. Patent 40 1,757,434, May 6, 1930. A tension device 90 which is similar to the tension device or element 17 shown in the Lawson et al. patent, performs the same function with respect to the main yarns fed through the levers 20. For the auxiliary or 45 plating threads or yarns such as 54 a thread or yarn tensioning element 91 is provided, said tensioning element being similar to the element 90 and being fastened to plate 89 as by screws 92.

During the knitting of the leg of the stocking, 50 toe 50 of the lever 48 is in contact with the drum as indicated at Fig. 7. As the knitting of a heel is about to commence, continued rotation of the drum 5 in the direction of the arrow, causes the cam 51 to engage the toe 50 of the lever 48 and 55 rock lever 48 against the tension of the leaf springs 82, the yarn levers 55, 56, 57 being thereby maintained in an elevated position during the knitting of the heel. When the knitting of the heel is completed the drum 5 is further advanced 60 permitting the toe 50 to drop off the cam 51 and onto the surface of the drum 5 between the cam 51 and the cam 52 where it remains during the knitting of the sole of the stocking, the several yarn guides 55, 56, 57 being permitted to be moved to 65 an operative position as dictated by the cams such as 37 on the drum 36. Upon completing the knitting of the sole of the stocking the drum 5 is further advanced thus causing the cam 52 to engage toe 50 of the lever 48 and again rock the 70 said lever thereby again causing the guides 55, 56, 57 to be elevated where they remain throughout the knitting of the toe.

Fig. 10 shows the needles, after having passed the auxiliary guides 55, etc., as being elevated to 75

clear the latches of the loops drawn during the previous course of knitting; the latches on the needles are of sufficient length to prevent the threads 54 fed through the guides 55, 56, 57 drop-
5 ping off the said latches.

From the foregoing description in connection with the drawings it will be evident that any one or more of the usual yarn levers 20 may be maintained in feeding position for any desired length 10 of time for the purpose of feeding a main yarn or yarns to the needles while one or more of the plating guides 55, 56, 57 may be maintained in the feeding position indicated in Fig. 4 for any desired length of time and another guide or guides may be 15 substituted for the first guide or guides thus providing for a ready change in the relations of a plurality of main and a plurality of plating yarns or threads.

Further variations in pattern effects may be 20 obtained by jacks for selectively controlling the needles in a manner similar to that shown in British Patent 267,109.

As is shown in Fig. 10, the lower or feeding ends 25 of the guides such as 57 feed their threads in the hooks of the needles at a lower level than the main guides 20 feed their yarns in the hooks of the said needles; as a consequence of the lower feeding positions of the guides 55, 56, 57 a better 30 plating separation between the plating and body threads is maintained.

Where, in the foregoing description and in the appended claims, reference is made to yarns or threads, it is to be understood that the terms are interchangeable, although for convenience the 35 main yarns or threads are sometimes referred to as "yarns" and the plating threads or yarns are sometimes referred to as "threads".

In the foregoing description specific terms have been used for descriptive purposes only without 40 the intention of limiting the invention to the precise construction shown, as an instance: latch needles are shown and described although, obviously, other forms of needles may be used in place of latch needles.

45 We claim:

1. A circular knitting machine having a rotary needle cylinder and stationary latch ring, means carried by the latch ring for feeding one or more 50 yarns to the needles, a recess in the latch ring spaced from the yarn feeding means, in combination with interchangeable plating guides for feeding threads to the needles and means for moving the said plating guides individually and as desired in the recess in the latch ring and between the 55 said latch ring and the needles, and cam means for controlling the needles to knit a said yarn and a said thread at the same feeding station.

2. A circular knitting machine having a rotary needle cylinder and stationary latch ring, means 60 carried by the latch ring for feeding one or more yarns to the needles, a recess in the latch ring spaced from the yarn feeding means, in combination with interchangeable plating guides and means for moving the said plating guides individually and as desired in the recess in the latch ring and between the 65 said latch ring and the needles, the plating threads being fed to the needles at a level below the level where the yarns are fed to the needles.

70 3. In a circular knitting machine having means for feeding one or more main yarns to the needles, a latch ring and a bracket carried thereby, plating 75 thread guides slidably mounted in the bracket to move vertically to a position between the needles and latch ring to feed threads to the needles; and

cam means for controlling the needles to knit a said yarn and a said thread at the same feeding station.

4. In a circular knitting machine having means for feeding one or more main yarns to the needles, a latch ring and a bracket carried thereby, thread guides slidably mounted in the bracket to move vertically to a position between the needles and latch ring to feed threads to the needles at a level 5 below the level of feeding of the main yarns to the 10 needles.

5. A circular knitting machine having a plurality of guides for interchangeably feeding main 15 threads or yarns to the needles, in combination with supplemental means located in advance of the main yarn feeding means interchangeably to feed plating threads to the needles, the feeding of plating threads being effected at a level below that of the feeding of the main yarns, and cam means for controlling the needles to knit a said yarn and 20 a said thread at the same feeding station.

6. An independent needle knitting machine, means for feeding one or more yarns to the needles and supplemental means for feeding one or more plating threads to the needles at the same 25 feeding station, the feeding level of the plating threads being below the feeding level of the yarns.

7. A circular knitting machine having a rotary needle cylinder and stationary latch ring, means carried by the latch ring for feeding one or more 30 yarns to the needles, a recess in the latch ring spaced from the yarn feeding means, and in advance of the yarn feeding means, in combination with interchangeable plating guides and means for moving the said plating guides individually and as desired in the recess in the latch ring and between the said latch ring and the needles, 35 and cam means for controlling the needles to knit a said yarn and a said thread at the same feeding station.

8. In a circular knitting machine having means for feeding one or more main yarns to the needles, a latch ring and a bracket carried thereby, thread guides slidably mounted in the bracket to move vertically to a position between the needles and 45 latch ring to feed threads to the needles, said thread guides being located in advance of the yarn feeding means.

9. In a circular knitting machine having means for feeding one or more main yarns to the needles, 50 a latch ring and a bracket carried thereby, thread guides slidably mounted in the bracket and located in advance of the yarn feeding means, and cam means for controlling the needles to knit a said yarn and a said thread at the same feeding 55 station.

10. An independent needle knitting machine, means for feeding one or more yarns to the needles and supplemental means located in advance of the yarn feeding means for feeding one 60 or more plating threads to the needles, the feeding level of the plating threads being below the feeding level of the yarns, and cam means for controlling the needles to knit a said yarn and a said thread at the same feeding station.

11. Thread feeding means for a knitting machine including a pattern mechanism and movable thread guides, the thread guides being normally maintained in feeding relation with respect to the needles, and means for selectively acting 70 upon the said thread guides to move them to inoperative position, said means including slides pins for operatively acting upon the thread guides and levers for operative engagement with the pins and means connecting the levers with the pattern 75

mechanism for selectively determining which of the thread guides shall be in feeding position.

12. Thread feeding means for a knitting machine including a pattern mechanism and slideable thread guides, the thread guides being normally maintained in feeding relation with respect to the needles, and means for selectively acting upon the said thread guides to move them to inoperative position, said means including levers con-

nected to the thread guides and slideable pins in engagement with the said levers and other levers for operatively engaging the pins and other means connecting the levers with the pattern mechanism for selectively determining which of the thread guides shall be in feeding position.

ROBERT H. LAWSON.
ARTHUR N. CLOUTIER.
